(57) **CLAIM**

The ornamental design for a dumbbell, as shown and described.

DESCRIPTION

FIG. 1 is a top perspective view of a dumbbell showing my new design;

FIG. 2 is a bottom perspective view of the dumbbell of FIG. 1;

FIG. 3 is a front view of FIG. 1;

FIG. 4 is a left side view of FIG. 1;

FIG. 5 is a top view of FIG. 1; and,

FIG. 6 is a bottom view of FIG. 1.

The broken line showing of the dumbbell is included for the purpose of illustrating portions of the article and forms no part of the claimed design.
